UNITED STATES PATENT OFFICE.

HENRY W. DODSON, OF LOS ANGELES, CALIFORNIA.

ASSEMBLY REEL.

Application filed April 20, 1926. Serial No. 103,407.

This invention relates to improvements in devices commonly known as assembly reels largely employed in laundries and similar establishments.

5 An object of this invention is to provide an improved assembly reel in which there is an improved mechanism for rotating the reel from one position to another and locking the reel in its various positions.

10 With the foregoing and other objects in view which will be made manifest in the following detailed description and specifically pointed out in the appended claims, reference is had to the accompanying drawings for an illustrative embodiment of the invention, wherein:

Figure 1 is a top plan view of the improved assembly reel,

Fig. 2 is a side elevation of the reel taken 20 in the direction of the arrow 2 upon Fig. 1,

Fig. 3 is an end elevation taken in the direction of the arrow 3 upon Fig. 2,

Fig. 4 is a vertical section taken on the line 4—4 of Fig. 2, and

25 Fig. 5 is an end elevation taken in the direction of the arrow 5 upon Fig. 2.

Referring to the accompanying drawings wherein similar reference characters designate similar parts throughout, the improvement is embodied upon an assembly reel of the conventional construction consisting of end supporting members 10 and 11 which serve as supports for trunnions 12 provided on end members 13 and 14 of the reel. These 30 end members are connected by radial shells or partitions 15 which carry conventional pins 16 adapted to receive the key tags on the articles of clothing which are placed on the reels. In the drawing a large sized reel 35 is disclosed, which has a center or intermediate circular member 17 which rests on rollers 18 on a circular support 19, thus serving to support the center of the reel in the case of a long reel. It will be readily 40 understood, however, that this construction is in no way essential to the improvement 45 constituting the invention.

The invention resides in providing an improved mechanism for rotating the reel, and 50 to accomplish this, the end members 13 and 14 have gear teeth 20 formed upon their peripheral surfaces. These gear teeth on the end members 13 and 14 mesh with pinions 21 and 22 which are keyed or otherwise 55 fastened to a longitudinal shaft 23 which is rotatably mounted in the end supports 10

and 11. On one end of the shaft 23 there is keyed or otherwise secured a worm wheel 24, and the worm wheel 24 meshes with the worm 25 provided on an actuating shaft 26 60 rotatably mounted in bearings 27 on the support 10. The actuating shaft is adapted to be rotated by a hand wheel 28 thereon.

The operation of the improved device is as follows: When it is desired to rotate the 65 wheel from one position to another, the hand wheel 28 is rotated, rotating the actuating shaft 26. The worm 25 drives the worm wheel 24 and causes the shaft 23 to be rotated, and as the pinions 21 and 22 mesh 70 with the gear teeth on the peripheral surfaces of the end members 13 and 14, the reel will be rotated. However, when the reel has been moved into the desired position on discontinuing rotation of the actuating shaft 75 26, the reel will be locked in that position because of the engagement of the worm wheel 24 with the worm 25.

By the improved construction it will be 80 readily appreciated that the reel will be rotated by applying a force at both ends thereof thus eliminating any strains which are present in prior constructions wherein the reel is rotated by applying a force to one end member only. The improved construction 85 is a decided improvement over those prior constructions wherein there is a worm wheel mounted on one of the end members about its trunnion 12, which worm wheel meshes with a worm on the actuating shaft. 90 Such constructions have been found disadvantageous in that there is usually a considerable amount of loose play permitting the reel to be rocked or to wobble in any adjusted position. Such loose play is effectively eliminated by employing the gear teeth 20 and causing the end members to function as large gears driven by small pinions 21 and 22. 95

It will be understood that various changes 100 in the detail of construction may be made without departing from the spirit and scope of the invention as defined by the appended claims.

I claim:

1. An assembly reel for use in laundries comprising end members, radial shelves mounted between the end members, pins carried by the shelves, means providing gear teeth on one of the end members, a pinion meshing with the gear teeth, a worm wheel rigid with the pinion, an actuating shaft 110

carrying a worm meshing with the worm wheel, and a hand wheel mounted upon the actuating shaft for rotating it.

2. An assembly reel for use in laundries comprising supports, an assembly reel having end members rotatably mounted upon said supports, means connecting said end members and supported thereby, adapted to support articles to be, or which have been laundered, means providing gear teeth upon the peripheral surfaces of both of said end members, a shaft extending longitudinally of the assembly reel and carrying pinions meshing with the said gear teeth, a worm wheel on the shaft, an actuating shaft rotatably mounted upon one of said supports, a worm on the actuating shaft meshing with said worm wheel, and means for rotating said actuating shaft.
3. An assembly reel for use in laundries comprising supports, an assembly reel rotatably mounted upon said supports having circular end members, means connecting said end members and supported thereby, adapted to support articles to be, or which have been laundered, a shaft extending longitudinally of the reel adjacent the peripheral surfaces of the end members, means carried by the shaft engaging the peripheral surfaces of the end members, and means for rotating the shaft to produce rotation of the reel.
4. An assembly reel for use in laundries comprising supports, an assembly reel rotatably mounted upon said supports having circular end members, means connecting said end members and supported thereby, adapt-

ed to support articles to be, or which have been laundered, a shaft extending longitudinally of the reel adjacent the peripheral surfaces of the end members, means carried by the shaft engaging the peripheral surfaces of the end members, a worm wheel on the shaft, an actuating shaft rotatably mounted upon one of said supports, a worm carried by the actuating shaft meshing with the worm wheel, and means for rotating the actuating shaft.

5. An assembly reel for use in laundries comprising supports, an assembly reel having end members rotatably mounted upon the supports, means connecting said end members and supported thereby, adapted to support articles to be, or which have been laundered, there being gear teeth upon the peripheral surface of one of said end members, a pinion meshing therewith, a worm wheel for rotating the pinion, an actuating shaft, a worm on the actuating shaft meshing with the worm wheel, and means for rotating the actuating shaft.

6. A laundry machine comprising in combination, a cylindrical container, said container having a plurality of radial shelves therein, pins on said shelves adapted to retain bags of laundry, said container being mounted on a standard so as to be rotatable thereon, means for rotating said container, and means for locking the same in any predetermined position.

In testimony whereof I have signed my name to this specification.

HENRY W. DODSON.
